LOCATING JIG DEVICE FOR USE IN DRILLING HOLES IN RACKET HEADS

Horace W. Hall, Newton, Mass.

Application November 30, 1945, Serial No. 631,915

3 Claims. (Cl. 144—93)

1

This invention relates to a locating jig device, particularly to one that will automatically locate an article, such as a playing racket, in a predetermined position.

The principal object of my invention is to provide a locating jig which correctly locates the part of the article to be drilled with the aid of the article itself.

In the drilling of articles such as tennis rackets, it is important that the holes drilled therein to receive the strings, shall be located at predetermined points at both the inside and outside of the bowhead of the racket. In order to accomplish this previously the operator depended upon his eye, and sometimes a mark was made on the top of an outside jig by which the drill was alined to be sure the direction of the drill as it cut a hole in the bow head was correct.

My invention eliminates this dependency upon the eye, since it is only necessary to start the drill at the correct point and my device, with the aid of the article to be drilled, will correctly position the latter.

The foregoing and other objects which will appear as the nature of the invention is better understood, may be accomplished by a construction, combination and arrangement of parts, such as is disclosed by the drawings and specification. The nature of the invention is such as to render it susceptible to various changes and modifications, and, therefore, I am not to be limited to said disclosure; but am entitled to all such changes therefrom as fall within the scope of my claims.

In the drawings:

Figure 1 is a plan view of the work board of my locating jig device and a drill, showing a playing racket on said work board having a hole drilled therein.

Figure 2 is a right side elevational view of said work board.

Figure 3 is a side elevational view of a locating member for my work board.

Figure 4 is a side elevational view, partly in section, of my locating jig device showing a playing racket on the work board with a drill extending through the bowhead thereof.

Figure 5 is a front elevational view of my device.

Figure 6 is a fragmentary sectional view taken on the line 6—6 of Figure 5.

As illustrated, my locating jig device has a stationary base 10 for support which has a laterally extending portion 12 that rests on the floor, and from which a vertical portion 14 extends up-

2

wardly. Also another vertical portion 16 extends upwardly. An arm 18 extends from said vertical portion 14, and has a bearing portion 19 at one end.

5 Additional supporting means 20 are vertically movable with respect to said base 10, having side portions 22 and V-shaped extensions 24 at both sides thereof which permit said support 20 to slide vertically on the surfaces of said vertical portion 14 between two guide strips 26 which are fastened to said vertical portion 14 by bolts 28.

In said upwardly extending portion 16 a lead screw 30 is threaded which extends to and is held loosely in a boss 32, that is part of said supporting means 20, by means of a pin 33 in a groove 34 in said boss 32. Said lead screw 30 is thereby permitted to revolve in said boss.

Through a hole 36 in said bearing portion 19 and also through another bearing portion 19a of 20 said vertical portion 16 a shaft 38 extends on the end of which is a miter gear 40 held thereto by a pin 41. It meshes with another miter gear 42 which is threaded on the said lead screw 30. A hand wheel 44 is fastened to said shaft 38, rotation of which will raise or lower said supporting means 20 as desired.

In said support 20 two grooves 21 are provided in which a slidable, work supporting structure 46 is slidably mounted that can move forwardly 30 and rearwardly by the operator as desired. At the front portion of said structure 46 are two bearing members 48 to which is pivotally mounted a work board foundation member 50 by means of pins 51, thus permitting said work board member 45 to pivotally move upwardly and downwardly to the desired angle by the operator. A vernier attachment 52 fixed to said supporting structure 50 serves as a guide in moving said work board foundation member 50 to a predetermined position.

40 A clamp screw 54 extends through a slot 55 in said vernier attachment 52, being threaded into a said slide portion 22. It is preferable to have a said vernier attachment on each said side portion 22, as shown in Figure 5. When it is correctly marked a predetermined slant of the work board 56, later described, can be obtained by merely pivotally moving said work board foundation member 50 so that the point on said vernier is opposite a certain marking on a said side portion 22.

45 Resting on said work board foundation 50 is a work board 56, on the surface of which rests the article or work to be drilled or otherwise worked upon. Said work board 56 is held in position by 50 screws 58 which extend into said foundation

member 50. Mounted upon the surface 60 of said work board 56 are exterior locating members 62 which are shown attached thereto by bolts 63 which extend through holes 64 in said foundation member 50 and are tightly held in predetermined positions by wing nuts 65. Said holes 64 are provided frequently, as shown in Figures 1 and 5 of the drawings, so the position of said locating members 62 may be changed when desired. Said members 62 have a perpendicular wall portion 74 at one end that serves as a step, and an inclined surface 75 is at the opposite end, as best shown in Figure 3 of the drawings. The racket handle H, when in a predetermined position, bears against said stop or wall portion 74, and when movement from one location member 62 to another is made said handle H is slid up said inclined surface 75 and into contact with said stop portion.

An intermediate or head-positioning portion of said work board 56, is preferably formed by a separate member 66 that is shown raised slightly above the surface of the adjoining portions of said board and is preferably made of a more durable material, such as a hard fiber, than other portions of said board 56, since the principal portion of the article or work R to be drilled rests directly thereupon. The said portion 66 has a cut-out portion 67 at the front for convenience of the operator and an opening 68 therein to allow a drill 70 and a chuck 71 therefor to extend therethrough and drill the article R. This head positioning portion 66 of my work board 56 is spaced from said locating member 62 a substantial distance so that a part of the article not to be worked upon is in contact with said members 62.

Set in said work board support 50 is a pin 72 against which said article R is pushed during the drilling operation, thereby causing said work supporting structure 46 to slide rearwardly, as will be explained more fully.

Said drill chuck 71 is set in a rotatable, but otherwise stationary shaft 76 that is supported in bearings 78 in supporting posts 80 that may rest on the floor. Any well known motor M or the like will serve to rotate said drill shaft 76 by means of a belt 82 and pulleys 84 as shown in Figure 4 of the drawings.

Set in said work supporting structure 46 is an extension portion 87 to which a coil spring 86 is attached which extends therefrom to a projecting member 88 on said supporting means 20. Said spring normally holds said supporting structure 46 in inoperative position so that the said drill 72 is out of contact with the work R, but when said work or article R is pushed against said pin 72 said structure 46 is moved rearwardly and said spring is put under tension as illustrated in Figure 4 of the drawings and thus it automatically causes said structure 46 upon release, to slide back to normal position.

In operation, my locating jig device as illustrated, is used to move a tennis or other playing racket R into contact with the rotating drill 70 to thereby bore holes through the bow head of said racket R, through which strings later extend. Said holes are bored through said bowhead from the inside to the outside at an angle, hence said work board 56 is in an inclined position. The inside surface of said bowhead has prick punches therein to indicate the starting point of the drill 70.

My jig device is adapted for use with articles that have an extension portion beyond the part

to be drilled, which in the case of a playing racket is a handle H. Said handle H extends to or beyond said exterior locating members 62, which are in predetermined positions to insure the correct location of the holes drilled in said racket bowhead, since when said handle H bears against the straight bearing surface 74 of a certain said locating member 62, the hole drilled in said bowhead will extend therethrough in a predetermined position. For instance, the first hole drilled in the racket R will be near where the handle H adjoins the bowhead, and which for convenience will be referred to as number one hole. The first locating member starting leftwardly at the front of my work board 56, is in a predetermined position so that when said handle H bears against said stop portion 74 the position of the hole drilled in said racket bowhead will be correct, and all the operator has to do is to start the drill at the prick point for said number one hole, the slant of said work board 56 being in the desired position so the slant of the hole will be as desired.

It will thus be seen that the operator merely has to push the racket against said pin 72 to force it on said sliding structure 46 up to said drill 70 and see that the drill starts at the correct or predetermined pin point on the racket, and a perfectly located hole will be drilled. Pressure on said racket R is thereupon released and said spring 86 draws said sliding structure 46 away from said drill to normal position, whereupon said racket handle H is slid over the slanting surface 75 of the next said locating member 62 until it rests against the said stop portion 74, and thus the racket is positioned correctly for drilling of the second hole in said bowhead. This operation is repeated until the holes in said racket bowhead have all been drilled. In Figure 1 of the drawings the racket H is shown positioned to have the third hole in the racket bowhead drilled, said handle H bearing against the third said locating member as shown.

What I claim is:

1. A locating jig device for use with a drill to drill holes in the head of an article that embodies a handle and said head, comprising a work board on which the article to be worked upon is adapted to be supported, and supporting means for said work board, said work board embodying a head-positioning portion at an intermediate portion thereof adapted to receive said head to be worked upon, and upstanding, locating members attached to said work board and spaced outwardly beyond said positioning portion at various distances and angles from the said holes being drilled and adapted to selectively engage said handle while said holes are being drilled.

2. A locating jig device for use with a drill to drill holes in the head of an article that embodies a handle and said head, comprising a work board on which the article to be worked upon is adapted to be supported, and supporting means for said work board, said work board embodying a head-positioning portion at an intermediate portion thereof adapted to receive said head to be worked upon, and upstanding, locating members attached to said work board and spaced outwardly beyond said positioning portion at various distances and angles from the said holes being drilled and adapted to selectively engage said handle while said holes are being drilled, said work board having a cut-out at the front thereof which extends from the front extremity 75 of said work board to said positioning portion.

3. A locating jig device for use with a drill to drill holes in the head of an article that embodies a handle and said head, comprising a work board on which the article to be worked upon is adapted to be supported, and supporting means for said work board, said work board embodying a head-positioning portion at an intermediate portion thereof adapted to receive said head to be worked upon, and upstanding, locating members attached to said work board and spaced outwardly beyond said positioning portion laterally and rearwardly thereof at various distances and angles from the said holes being drilled and adapted to selectively engage said handle while said holes are being drilled, said laterally spaced locating members being spaced from said positioning portion a greater distance than are said locating members spaced directly rearward.
